POWER LAWN MOWER

Charles W. Butler, Englewood, N. J., assignor to
Toro Manufacturing Corporation of Minnesota,
Minneapolis, Minn., a corporation of Minnesota

Application July 13, 1953, Serial No. 25,893

Term of patent 14 years

(Cl. D40—1)

To all whom it may concern:

Be it known that I, Charles W. Butler, a citizen of the United States of America, residing at Englewood, county of Bergen, New Jersey, have invented a new, original, and ornamental Design for a Power Lawn Mower, of which the following is a specification, reference being made to the accompanying drawings forming a part thereof, and in which:

Figure 1 is a perspective view of a power lawn mower viewed from the front and right-hand side, showing my new design;

Figure 2 is a perspective view thereof viewed from the front and left-hand side;

Figure 3 is a top plan view thereof;

Figure 4 is a rear elevational view thereof; and

Figure 5 is a bottom plan view thereof.

The characteristic features of the design reside in the solid line portion.

I claim:

The ornamental design for a power lawn mower, substantially as shown and described.
